FOOD AND BEVERAGE BLENDER

Leonard C. Smith, Baldwin, N. Y.

Application March 27, 1953, Serial No. 24,216

Term of patent 3½ years

(Cl. D44—1)

To all whom it may concern:

Be it known that I, Leonard C. Smith, a citizen of United States of America, residing at Baldwin, in the county of Nassau and State of New York, have invented a new, original, and ornamental Design for Food and Beverage Blender, of which the following is a specification, reference being had to the accompanying drawing, forming part thereof.

In the drawing:

Fig. 1 is a perspective view of a food and beverage blender showing my new design;

Fig. 2 is a top plan view of that shown in Fig. 1 with the cover removed; and

Fig. 3 is a bottom plan view thereof.

The tubing shown in broken lines is for illustrative purposes.

I claim:

The ornamental design for a food and beverage blender, substantially as shown and described.
